UNITED STATES PATENT OFFICE

2,547,783

FLUX BRIDGE TRANSFORMER

Charles C. Roe, Longview, Tex., assignor to R. G. LeTourneau, Inc., Stockton, Calif., a corporation of California

Application September 17, 1948, Serial No. 49,738

5 Claims. (Cl. 171—242)

1

The present invention relates to and it is an object to provide a novel transformer for supplying three phase transformed current at a predetermined value.

Another object of the invention is to provide a 3-phase transformer which employs a bridge between the primary and secondary coils thereof for the purpose of by-passing excess flux and preventing the secondary circuit from becoming overloaded.

It is also an object to provide a means of manual adjustment for this transformer in order to selectively vary the amount of current to be permitted in the secondary circuit.

It is an additional object to provide a transformer which may be used with an A. C. supply source which has a variable potential and cycle frequency, but which transformer will maintain a steady output of its secondary coil.

A further object is to provide a transformer of the above characteristics which will be simple in construction, easy to adjust, and economical to build.

These objects are accomplished by means of such structure and relative arrangement of parts as will fully appear by a perusal of the following specification and claims.

Referring to the accompanying drawing:

Figure 1 is a plan view of a transformer embodying my invention.

Figure 2 is a side elevation of this transformer showing the bridge inserted to its maximum depth.

Figure 3 is a flux diagram showing the path of flux during operation.

Referring now more particularly to the characters of reference on the drawings, the transformer shown consists of a three-legged core of stacked laminations 1 supported by and between mounting brackets 2 and clamping bars 3. The clamping bars are tightened and compress the laminations and hold them in position by bolts 4. On each leg of the transformer core a primary coil 5 is placed, and spaced therefrom on each leg a secondary coil 6 is also placed. This arrangement provides an air space 7 separating the primary and secondary coils. On one side of the transformer a laminated iron bridge 8, which will be referred to hereafter as a flux-bridge, is inserted into space 7. This flux-bridge is suspended from and supported by a triangular mounting pad 9 which is fastened to clamping bar 3 by means of two capscrews 14. Underneath bridge 8 and between it and core 1, a shim or

2

shims 10 of a non-magnetic material such as Micarta is placed.

It will be seen from this arrangement, that the bridge is secured in its position by the capscrews 14 and the shims 10, and this position may be regulated by loosening the capscrews, inserting more shims and then tightening the capscrews until the bridge is in firm engagement with the shims.

10 When there is no current being drawn from the secondary, this transformer performs in the same manner as certain conventional transformers, that is a magnetic flux travels around the iron core as at 12 and creates a potential in 15 the windings of the secondary. However, when the secondary is drawing current, and when this current reaches a predetermined value, the reluctance in the iron core is greater than the reluctance of the gap between the core and the bridge and the flux jumps the gap and completes 20 its circuit through the bridge. This method of by-passing the flux which is in excess of that required to maintain the predetermined current prevents any damaging overload from reaching 25 the device being supplied from the transformer.

In Figure 3, it will be seen that the flux created in the iron core 1 continues to be maintained at full strength in the core (as at 12) until the reluctance in the core (due to current in the secondary circuit) becomes so great that a portion of the flux will jump the gap and travel through the bridge since the path 13 offers a lesser reluctance.

From the foregoing description, it will be seen 35 that there has been produced such a 3-phase flux-bridge transformer as substantially fulfills the objects of the invention as set forth herein.

While this specification sets forth in detail the present and preferred construction of this 40 transformer, still in practice such deviations from such detail may be resorted to as do not form a departure from the spirit of the invention as described in the appended claims.

Having thus described the invention, the following is claimed as new and useful and upon which Letters Patent are desired:

1. A three-phase transformer having a three-legged core containing primary and secondary windings on each leg thereof, said core forming 50 a closed flux path, there being an air space between the two windings on each leg and a bridge of laminated magnetic material inserted in the air space in a manner to overlie each leg of the core which forms a direct flux path between corresponding primary and secondary windings, and

insulating shims between said core legs and the bridge, the total thickness of said shims being readily adjustable.

2. A three-phase transformer having a three-legged core containing primary and secondary windings on each leg thereof, said core forming a closed flux path, there being an air space between the two windings on each leg and a bridge composed of laminations of magnetic material inserted in the air space in a manner to overlie each leg of the core which forms a direct flux path between corresponding primary and secondary windings, and insulating shims between said core legs and the bridge, the total thickness of said shims being readily adjustable, said shims acting as an added reluctance to prevent the passage of flux through the bridge until such time as the reluctance in that portion of the core under the secondary windings becomes greater than the reluctance of the path composed of the shims and the bridge.

3. A three-phase transformer having a three-legged core containing primary and secondary windings on each leg thereof, there being an air space between these two windings on each leg, a bridge inserted in the air space and overlying each of the legs of the core and being insulated therefrom; said core supported by a mounting structure, a pad overlying opposite sides of said mounting structure, said bridge secured in position by being suspended from said pad, said pad being removably attached to said mounting structure.

4. A three-phase transformer comprising a three-legged magnetic material core containing primary and secondary windings on each leg thereof, an air space separating the two windings on each leg, and a bridge of magnetic material inserted in the air space and overlying each of the legs of the core and being insulated therefrom; said bridge being capable of bypassing a portion of the flux in the core when the reluctance of that portion of the core containing the secondary windings reaches a predetermined value; said core supported by a mounting struc-

ture, a pad overlying opposite sides of said mounting structure, said bridge secured in position by being suspended from said pad, said pad being removably attached to said mounting structure.

5. A three-phase transformer having a three-legged core containing primary and secondary windings on each leg thereof, said core forming a closed flux path, there being an air space between the two windings on each leg and a bridge inserted in the air space in a manner to overlie each leg of the core which forms a direct flux path between corresponding primary and secondary windings, and insulating shims approximately the same length as the bridge between said core legs and the bridge, the total thickness of said shims being readily adjustable, said shims acting as an added reluctance to prevent the passage of flux through the bridge until such time as the reluctance in that portion of the core under the secondary windings becomes greater than the reluctance of the path composed of the shims and the bridge; said core supported by a mounting structure, a pad overlying opposite sides of said mounting structure, said bridge positioned with its laminations perpendicular to said pad and said core and suspended from said pad, said pad being removably attached to said mounting structure by capscrews, said capscrews upon tightening causing the bridge to be in firm engagement with said shims.
